BLACK-OUT SHADE

Rollin P. Taylor and Robert E. Bingman, Detroit, Mich., assignors to General Motors Corporation, Detroit, Mich., a corporation of Delaware

Application June 24, 1942, Serial No. 443,270

4 Claims. (Cl. 160—114)

This invention relates to window curtains and has particular reference to a curtain to be used for blackouts or for photographic dark rooms.

Because of the danger of bombing of cities at nighttime, blackouts are desirable, and for the purpose of enabling the occupants of certain buildings to work by artificial light, the present curtain has been designed to blackout the windows and prevent the passage of light while at the same time permitting air to pass in and out of the building to give adequate ventilation. Completely to close a window during a blackout and not permit the passage of air is undesirable, and the thought of having a curtain which would be impervious to light and at the same time permit ventilation of a room led to the design of the blackout curtain of the invention.

The curtain itself comprises a plurality of zig-zag shaped blades or shutters which in their position of use or during a blackout are spaced from each other for the entire length of the window and extend laterally from side to side of the window. The apices of one zigzag element or shutter extend into the angles of the adjacent zigzag element or shutter so that there is an overlap. By painting the zigzag elements black, the light from one side, even if very intense, will not be transmitted to the other side. In other words, the observer from one side of the blackout curtain will be unable to see a light on the other side, and this substantially regardless of the intensity of the light. This is due to the speed of light, and its inability to pass around a sharp corner.

During the daytime, when there is no occasion to use the blackout curtain, or at nighttime when it is not desired to use the curtain, it may be raised by lifting the lowermost element of the curtain and causing the successive zigzag members to be picked up and nested at the top of the curtain. This will leave the window substantially unobstructed and move the curtain out of the way. All of the zigzag elements or blades of the curtain are interconnected by a plurality of fabric strips and this fabric folds when the curtain is raised.

On the drawings:

Figure 1 is a face view of the curtain positioned over a window and in the blackout position.

Figures 2 and 3 are enlarged sectional detailed views on the line 2—2 of Figure 1 with parts broken away and better to illustrate the construction. Figure 2 shows the curtain in lowered position, and Figure 3 in raised position.

Figure 4 is a sectional view on the line 4—4 of

Figure 2 with parts broken away better to illustrate the construction.

Figure 5 is a section on the line 5—5 of Figure 4 with parts broken away.

Figures 6 and 7 are sectional detailed views on the corresponding lines of Figure 4.

Figure 8 is a view corresponding to Figure 7 of a modification.

Figure 9 is a perspective view of the end of a zigzag member of Figure 8.

Referring to the drawings, the numeral 2 indicates any type of building provided with an opening 4 in which there is the usual glass window (not shown). The outside of the building 2 at the window opening 4 may be recessed as indicated at 6 for the reception of the blackout curtain or structure. The blackout curtain is built as a unit and may be applied to any window or window opening and is held in place by suitable brackets 7 attached to the window opening and to the frame 10 of the blackout curtain.

The blackout curtain is indicated as a whole at 8 and includes the outer frame 10. The upper part 9 of the frame 10 comprises the center frame member 12, the outer frame member 14, and the inner frame member 16. These members are united in any suitable way such as by the bolts and nuts 18. The upper frame member 9 has secured thereto a two-part frame member 20 comprising the outer element 22 and the inner element 24. The element 22 is secured to the inner frame bar 16 by means of the angle irons 26 and the screws 28, while the second frame element 24 is secured to the inner frame member 16 by means of the bolts and nuts 32. The lower part of this frame member 20 is zigzag in shape as shown to conform to the zigzag shape of the individual blades or shutters 34 of the curtain.

The bottom member of the frame of the blackout curtain is indicated at 36. This member 36 has secured thereto an outer member 38. A runner 40 is mounted in a groove in the top surface of the frame member 36 and this runner has inclined upper surfaces to fit into an inclined groove 42 formed in a movable lower frame member 44 forming a part of the curtain. The member 44 is in turn composed of an outer element 46 and an inner element 48 and these elements 46 and 48 are formed in zigzag shape and complementary to the zigzag shape of the upper frame element 20. The zigzag shape of the lower frame member 44 is adaptable to the zigzag shape of the blades or shutters 34.

The side members 50 of the frame for the curtain are channel shaped as is best shown in Fig-

ures 5 and 7. The channels 50 comprise the angle member 52 provided with a channel 54 at one of its upright ends. The second member of the channel 50 is indicated at 56 and comprises a box-like construction. This box-like construction is separable from the angle member 52 and is secured to the angle member by means of bolts 58 and nuts 60, the nuts 60 fitting into the channel 54. By loosening the nuts 60 and removing the bolts 58, the box-section construction 56 is removable from the angle iron 52.

The box-sectioned construction 56 has an inwardly projecting flange 62 and the angle member 52 has an inwardly projecting flange 64. These flanges 62 and 64 project toward each other but their ends are spaced from each other for a purpose which will later be described.

The blades or shutters 34 are zigzag shaped to conform to the zigzag shape of the upper frame member 20 and the lower frame member 44. These zigzag elements 34 may be made of any suitable material such as cardboard, wood, or metal, and all are united at both sides by means of the flexible strips 66, four of which are used as shown in Figure 1, but any suitable and desired number may be used.

The lower movable frame member 44 has secured thereto at each end, and projecting therefrom, a mounting bracket 68 which has thereon an axle 70 on which there is mounted a rotatable pulley 72. A retaining strap 74 is mounted on the bracket 68 around the pulley 72 to hold a cord or cable in place.

The center element or slat 73 of each zigzag shutter 34 is longer than the two lateral elements or slats 73a and 73b. These longer elements 73 project laterally deeper into the channels of the side frame members 50. The ends of the members 73 lightly contact a black felt strip 75 secured in the bottom of the channel. This construction effectively prevents light from passing through the curtain at the side edges thereof.

Similarly, the brackets 68 extend from the ends of the frame member 44 into the channel 50 while the frame member itself extends to the channel only. The width of each pulley 72 and its cord retaining strap 74 is greater than the width of the space between adjacent edges of the flanges 62 and 64. See Figure 7. The pulleys 72 will therefore travel up and down in the channels 50 when the frame member 44 is moved.

On the upper frame member 9 there is secured at one side a bracket 76 in which there is turnably mounted on an axle 78 a pulley 80. A second pulley 82 is turnably mounted on and intermediate the length of the frame member 9, but closer to the opposite side and adjacent a third pulley 84 mounted on an axle 86 secured to a bracket 88 mounted to the frame member 9. A fourth pulley 89 is mounted at the extreme end of the frame member 9. A fifth or double pulley 90 is mounted in a bracket secured to the frame member 9 between pulleys 84 and 89 and is so positioned that it will receive the cords 92 and 94 at each side of the curtain from the pulleys 84 and 89 and guide them through a tube 96 to the outside of the curtain. This structure is best shown in Figures 5 and 6.

The end 98 of the pull cord 94 is fastened by one of the bolts 32 as shown at 100 to the upper frame member 9 and the end 102 of the pull cord 92 is fastened by another of the bolts 32 as shown at 104 to the upper frame member 9. These cords are then trained in a downward direction around the lower pulleys 72 on the brackets 68

and then upward; the cord 92 then around the pulleys 80, 82 and 84 to the pulley 90 and the pull cord 94 then around the pulley 89 and to the double pulley 90; both then extend outward 5 through the guide tube 96. The cords 92 and 94 extend outwardly for a considerable distance as indicated in Figure 1 and each is provided with a knob 106 at its extremity. By grasping the cords 92 and 94 or the knobs 106 and pulling thereon the lower movable frame member 44 of the curtain will be raised and its ends slide in the channel 50 and as it moves upwardly it will successively pick up and nest each of the individual zigzag shutters or blades 34 until the extremity of the upward movement is reached. The position of the parts will then be as shown in Figure 3. The fabric strips 66 will fold as is shown, and all of the shutters will be nested into a compact position to leave the window open or unobstructed as indicated at 108. The cords may now be fastened to a suitable hook (not shown) secured to the wall of the building 2. This will hold the blackout curtain in the upper position and allow a free access of light and air.

By releasing the cords 90 and 92 from their hook, the lower movable frame member 44 and the individual blades will drop by gravity to the lowered position as shown in Figures 1 and 2, and in this position the blackout curtain may be 20 latched or locked by means of a latch 110 best shown in Figures 2, 3, and 4. This latch member 110 has the hook 112 at its inner end which engages over a pin 114 mounted in the lower movable frame member 44. The frame member is 30 provided with a suitable recess 116 to enable the hook 112 to swing over and away from the pin 114. The catch is journaled in a bearing 118 mounted in the lower stationary frame member 35 36 and the outer part of the catch is provided 40 with an elongated swingable handle 120 to operate the catch. Preferably, two catches are provided, but as many as desired may be used.

Figures 8 and 9 show a modification. The channel 50 has no inwardly projecting flanges 52 and 62 but has plain sides throughout its length. The ends of the shutters or blades 73, 73a and 73b are differently formed or shaped in that all three are the same length and extend well toward the bottom of the channel. The ends are 50 slightly tapered as is best seen at 122 in Figure 8, and a triangular piece 124 is inserted between the ends of blades 73 and 73b. This piece 124 may be secured in any suitable way such as by metal fasteners, stitching or the like. The tapered construction will readily allow the succeeding zigzag elements to nest when they are raised as shown in Figure 3 to expose the window.

The construction of Figures 8 and 9 is preferred because it effectively excludes the passage 60 of any light at the curtain edges and is more economical to construct.

We claim:

1. In a blackout curtain for application to a window, a frame, a plurality of zigzag shutter elements of light absorbing material mounted in the frame, each element comprising at least 65 three angularly related slats interconnected to prevent the passage of light therethrough, means to interconnect the elements, said elements being in spaced relation when used as a blackout curtain to cover the window, a movable frame member at the bottom of the curtain, a pull cord attached to said movable frame member and adapted to be operated to raise said frame member, the operation of said cord causing the movable

frame member successively to pick up the shutter elements and nest them against the lower part of the upper member of the frame, and means integral with the zigzag elements partially to close the ends of the said elements to aid in preventing the passage of light.

2. In a blackout curtain for application to a window, a frame, a plurality of interconnected zigzag shutter elements of light absorbing material supported in said frame, each element comprising at least three angularly related slats interconnected to prevent the passage of light therethrough, said elements in their lowered position being in spaced overlapping relation to prevent the passage of light therebetween, a deep channel at each side of the frame forming the frame sides, the ends of the shutter elements extending deeply into the channel to closely adjacent the bottom thereof, a triangular piece connected to the ends of each shutter element partially to close the ends thereof and to cooperate with the channels to prevent the passage of light at the edge of the curtain, and means to enable the shutter elements to be raised and nested at the top of the window to expose the window opening.

3. In a ventilating blackout curtain, for ap-

plication to a window frame, having side members of a deep channel section, a plurality of interconnected shutter elements of light absorbing material of Z section, each element having means at its ends to close one angle of the Z to prevent the passage of light, the ends of the shutter elements extending into the channels to prevent the passage of light at the edge of the curtain, said elements in their lowered position being in spaced overlapping relation to prevent the passage of light therebetween.

4. In a ventilating blackout curtain, for application to a window frame, having side members of a deep channel section, a plurality of interconnected shutter elements of light absorbing sheet material forming a closed Z section of three angularly related surfaces, each element having closure means at its ends attached between two of the surfaces to close one angle of the Z to prevent the passage of light, the ends of the shutter elements extending into the channels to prevent the passage of light at the edge of the curtain, said elements in their lowered position being in spaced overlapping relation to prevent the passage of light therebetween.

ROBERT E. BINGMAN.

ROLLIN P. TAYLOR.
